UNITED STATES PATENT OFFICE.

GOLIAT DAVISON, OF ST. LOUIS, MISSOURI, ASSIGNOR OF ONE-HALF TO CARL NUSBAUM, OF BROOKFIELD, MISSOURI.

DESIGN FOR A SHOE-UPPER OR SIMILAR ARTICLE.

52,525.

Specification for Design.

Patented Oct. 8, 1918.

Application filed February 17, 1917. Serial No. 149,365. Term of patent 7 years.

To all whom it may concern:

Be it known that I, GOLIAT DAVISON, a subject of the King of Roumania, who has announced his intention of becoming a citizen of the United States, and a resident of the city of St. Louis and State of Missouri, have invented a new, original, and ornamental Design for a Shoe-Upper or Similar Article, of which the following is a specification, reference being had to the accompanying drawing, forming part thereof.

The figure is a view of a shoe showing my new design in full lines, the rest of the shoe being shown in dotted lines. The design may be embodied in spats and hose as well as in shoe uppers.

I claim:

The ornamental design for a shoe upper or similar article, as shown.

GOLIAT DAVISON.
